DESIGN FOR A NECKLACE OR LIKE ARTICLE

Harry Steinbach, New York, N. Y.

Application April 1, 1947, Serial No. 138,083

Term of patent 3½ years

(Cl. D45—16)

To all whom it may concern:

Be it known that I, Harry Steinbach, a citizen of the United States of America, and residing in the city of New York, county and State of New York, have invented a new, original, and ornamental Design for a Necklace or like article, of which the following is a specification, reference being made to the accompanying drawing, forming part thereof.

Fig. 1 shows a front view of the necklace or like article, illustrating my new design;

Fig. 2 is a bottom plan view of the necklace of Fig. 1.

The links of the necklace or like article are repeated throughout the length thereof as indicated by the broken line showing.

I claim:

The ornamental design for a necklace or like article, substantially as shown and described.

HARRY STEINBACH.
